(57) **CLAIM**

The ornamental design for an eye lens implanter, as shown and described.

DESCRIPTION

FIG. 1 is a bottom and front perspective view of an eye lens implanter in a closed working position, showing our new design;

FIG. 2 is a top and rear perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a bottom plan view thereof;

FIG. 8 is a top plan view thereof;

FIG. 9 is a bottom and front perspective view thereof in an open lens inserting position;

FIG. 10 is a top and rear perspective view thereof;

FIG. 11 is a front elevational view thereof;

FIG. 12 is a right side elevational view thereof;

FIG. 13 is a rear elevational view thereof;

FIG. 14 is a left side elevational view thereof;

FIG. 15 is a bottom plan view thereof;

FIG. 16 is a top plan view thereof; and,

FIG. 17 is an enlarged view of the top section of the eye lens implanter, shown in FIG. 10.
